UNITED STATES PATENT OFFICE.

ADOLPH RUBIN, OF ST. LOUIS, MISSOURI, ASSIGNOR TO SIEBER PRODUCTS MFG. CO., OF ST. LOUIS, MISSOURI, A CORPORATION OF MISSOURI.

REFRIGERATOR LOCK.

Application filed March 20, 1924. Serial No. 700,600.

To all whom it may concern:

Be it known that I, ADOLPH RUBIN, a citizen of the United States, residing at St. Louis, Missouri, have invented a certain new and useful Improvement in Refrigerator Locks, of which the following is a full, clear, and exact description, such as will enable others skilled in the art to which it appertains to make and use the same.

10 This invention relates to spring-actuated locks of the kind that are used on refrigerators and ice boxes for retaining the door of the refrigerator in its closed position.

One object of my present invention is to provide a lock of the general type mentioned in which the spring that actuates the latch is combined with the casing of the lock in a novel manner that permits said spring to be removed easily for inspection, repair or 20 replacement without the necessity of disconnecting the casing of the lock from the door on which it is mounted.

Another object is to provide a compact, inexpensive and highly efficient lock for 25 refrigerators and ice boxes which is constructed in such a manner that the movement of the handle in a direction to disengage the latch from the keeper causes the latch to be held in a position wherein it will clear the keeper during the operation of opening and closing the door and will move automatically into engagement with the keeper at approximately the time the door reaches its 30 fully closed position, thereby reducing the tendency of the keeper to work loose and wear rapidly as occurs in locks of the kind in which the latch strikes against the keeper and drags over same each time the door is moved into its closed position.

40 Another object is to provide a lock of the character referred to that is equipped with a keeper of novel design that can be adjusted easily to compensate for wear on the door gasket or on the latch or portion of the keeper with which the latch co-operates, or 45 adjusted to adapt the keeper to doors of different thicknesses.

And still another object is to provide a lock, which, in addition to having the desirable characteristics above pointed out, is so constructed that it can be adjusted easily to adapt it to right and left hand doors. Other objects and desirable features of my invention will be hereinafter pointed out.

55 Figure 1 of the drawings is a front eleva-

tional view, illustrating my improved lock arranged in operative position on a refrigerator or ice box.

Figure 2 is a side elevational view of said lock on a reduced scale. 60

Figure 3 is a rear elevational view of said lock; and

Figure 4 is a detail view, illustrating the construction of the removable member in the upper portion of the casing that serves as 65 an abutment for the spring which actuates the latch.

Referring to the drawings which illustrate the preferred form of my invention, A designates the casing of the lock which is 70 adapted to be connected by screws or other suitable fastening devices 1 to the door W of a refrigerator or ice box, B designates the latch of the lock, C designates the keeper which is adapted to be mounted on the front 75 wall Y of the refrigerator in such a position that it will co-operate with the latch B to hold the door in its closed position, and D designates the handle of the lock that is used to disengage the latch B from the 80 keeper C.

The latch B is reciprocatingly mounted in the casing A in such a way that a portion of said latch projects laterally through a slot 11 in one of side walls of the casing 85 A, and said latch is combined with a coiled expansion spring E that normally exerts pressure on said latch in a direction tending to move it towards the keeper C. In the lock herein shown the keeper C is arranged 90 under the latch, and accordingly, the spring E is so disposed that it normally exerts a downward thrust on the latch. The handle D is pivotally mounted on the front side of the casing A and is combined with the latch 95 B in such a way that forward movement of said handle causes the latch B to be moved upwardly against the force of the spring E. Preferably, the handle D is pivotally connected at its lower end by means of a horizontally-disposed pin 2 to a pair of forwardly-projecting lugs 3 on the front wall 100 of the casing A, and said handle is provided with a pair of angularly-disposed arms 4 that project rearwardly through vertical slots 5 in the front wall of the casing and enter openings 6 in the latch B, as shown more clearly in Figures 2 and 3. This method of combining the handle D with the latch B enables the lock to be changed 105

110

easily to adapt it to right hand doors and left hand doors by simply reversing the latch B so that it will project laterally through a similar slot 11 in the other side 5 wall of the casing; such a structure is inexpensive to manufacture and easy to assemble, and as there is a direct connection between the handle and the latch, the handle will be restored to its normal position in 10 close proximity to the casing when the latch moves downwardly into engagement with the keeper at the completion of the operation of closing the door.

Various means can be used for guiding 15 the latch B, but I prefer to equip the casing A with a vertically-disposed rod F that passes through a tubular portion 8 on the latch B, said rod being removably mounted in the casing A with its lower end portion 20 projecting into a hole in the bottom wall of the casing and its upper end portion projecting through a member G that is removably mounted in a tubular portion 9 on the casing A located at the upper end of said 25 casing. The rod F is also used as a guide for the spring E that actuates the latch B, said spring being mounted on said rod between the tubular portion 8 of the latch B and an adjustable tensioning device 10 that 30 bears against the underside of the removable member G in the tubular portion 9 of the casing.

As previously stated, the latch B is so 35 constructed and arranged that after it has been disengaged from the keeper C it will be maintained in a position wherein it does not drag over the keeper during the operation of opening or closing the door, but will be caused to move automatically into 40 engagement with the keeper at approximately the time the door reaches its fully closed position. This highly desirable result is effected by forming a shoulder 11^a in one edge of the slot 11 in the side wall 45 of the casing A through which the latch B projects laterally and combining the spring E with said latch in such a way that said spring normally exerts pressure on said latch in a direction tending to hold it 50 pressed tightly against the edge of the slot 11 in the casing that is provided with the shoulder 11^a. Consequently, when the handle D is swung forwardly to move the latch B upwardly out of engagement with the 55 keeper C, said latch will snap into engagement with the shoulder 11^a on the casing A as soon as said latch moves upwardly high enough to cause the lower edge of same to clear said shoulder. After the latch has 60 engaged the shoulder 11^a it remains in an elevated position high enough above the keeper C to clear same when the door is moving into its open position or into its closed position, but just as the door reaches 65 its fully closed position a tripping device

12 on the keeper comes into contact with the latch and disengages it from the shoulder 11^a, thereby permitting the latch to move downwardly into engagement with the concave seat in the keeper under the influence 70 of the spring E. As shown in Figure 3, the spring E is provided at its lower end with an extension 13 that projects into a notch 14 in the tubular portion 8 of the latch, and said spring is provided at its upper end with an extension 15 that projects into a notch 75 in the tensioning device 10, previously referred to. This tensioning device 10 is held against rotary movement by a means that will be hereinafter described, and consequently, the spring E will act as a torsion spring that will move the latch B into engagement with the shoulder 11^a on the casing and hold it in engagement with said shoulder after the latch has been disengaged 80 from the keeper, and will act as an expansion spring to move the latch downwardly into engagement with the keeper after said latch has been disengaged from the shoulder 11^a by the tripping device 12 on the keeper. 85

In locks of the type to which my invention relates it is necessary to frequently inspect, repair or replace the spring that actuates the latch, and in order that this may be done without removing the casing of the lock from the door on which it is mounted, I provide the casing with the removable member G, previously referred to, that acts virtually as an abutment for the spring E 90 and which is mounted in the casing A in such a way that it can be removed easily, thus enabling the spring E to be withdrawn upwardly through the tubular portion 9 of the casing. As shown in Figure 4, the member G consists of a sleeve that surrounds the upper end portion of the guide F and fits snugly in the tubular portion 9 of the casing of the lock, said sleeve being retained in position by a horizontally-disposed pin 16 that passes transversely 95 through the tubular portion 9 of the casing, through the sleeve G and through the guide rod F. A set screw 17 that is mounted in the upper end portion of the guide rod F is adapted to be moved into engagement 100 with the pin 16 after said pin has been positioned, so as to lock said pin and prevent it from moving into a position to release the member G that holds the spring E under compression. The tensioning device 10, previously referred to, consists of an annular-shaped member arranged on the guide rod F beneath the member G and provided with a plurality of holes 18, any one of which is adapted to receive a locking pin 19 that projects outwardly through a horizontally-disposed slot 20 in the tubular portion 9 on the casing of the lock. When it is desired 110 to vary the tension of the spring E the locking pin 19 is removed from the tension- 115

ing device 10, and said device 10 is then rotated in a direction to wind up said spring. After said spring has been set at the desired tension the locking pin 19 is replaced in the tensioning device 10. Owing to the fact that the spring E is constantly exerting pressure on the tensioning device 10 in a direction tending to rotate said device, the locking pin 19 in said device will be held in sufficiently snug engagement with one end of the slot 20 in the tubular portion 9 of the casing to eliminate the possibility of said locking pin 19 becoming accidentally disengaged from the tensioning device. From the foregoing it will be seen that the tension of the spring E can be increased easily by manipulating the tensioning device 10 and arranging the locking pin 19 in a different hole 18 of said tensioning device, and when it is desired to remove the spring E from the casing of the lock to inspect, repair or replace said spring, this can be accomplished easily by releasing the set screw 17, then removing the transversely-disposed locking pin 16 and thereafter withdrawing the member G from the tubular portion 9 on the casing of the lock. In order to compensate for wear on the door gasket or on the keeper and latch, and in order to adapt the lock to doors of different thicknesses, I adjustably mount the keeper C on a shank H that projects forwardly from a plate 27 that is adapted to be connected by screws or other suitable fastening devices 21 to the front wall Y of the refrigerator. The shank H is of substantially diamond shape in cross section, as shown in Figure 1, and the keeper C is provided with a split portion that surrounds said shank and which is adapted to be drawn into snug engagement with same by tightening a screw 22 that passes transversely through the lower end of said split portion at a point below the shank H. By loosening the screw 22 the keeper C can be adjusted longitudinally of the shank H into such a position that the latch B of the door can always be maintained in sufficiently snug engagement with the keeper to keep the door tight, even after the door gasket or the latch and keeper have become worn. When the lock is to be used with a comparatively thick door, the keeper C can be adjusted longitudinally of the shank H away from the supporting plate 27 to which the shank is connected, and when the lock is to be used with a comparatively thin door, the keeper can be adjusted longitudinally of the shank towards the plate 27. As previously stated, the latch B of the lock can be reversed so as to adapt the lock to either right hand doors or left hand doors, and this is also true of the keeper, due to the fact that the tripping device 12 on the keeper is arranged in vertical align-

ment with the shank H that sustains the keeper and the keeper is removably mounted on a shank H which is carried by a plate 27 that can be turned upside-down from the position shown in Figure 1 when it is desired to use the lock with a right hand door instead of a left hand door, as shown in said figure.

In order that the latch B may be disengaged from the keeper C by a person standing on the inside of the door W, a handle operating member I is slidably mounted in the casing A at a point above the pivot pin 1 of the handle D, said handle operating member I projecting inwardly through the door W, as shown in Figure 2, and being provided at its front end with a cross piece 23 that is adapted to strike against a lug 24 on the handle when said handle operating member is pushed forwardly, the forward movement imparted to said handle by the member I causing the latch to be moved upwardly out of engagement with the keeper. If desired, the handle operating member I may be provided at its rear end with a hand piece 25 that is detachably connected to same by a fastening device 26. With a handle operating member of the construction above described it is only necessary to bore a horizontal hole in the door to receive the portion of the member I that projects inwardly through the door. After the casing of the lock has been fastened to the door and the handle operating member I has been arranged in operative position in the door, the hand piece 25 is secured to the inner end of said handle operating member by means of the fastening device 26.

Having thus described my invention, what I claim as new and desire to secure by Letters Patent is:

1. A door lock, comprising a casing, a latch reciprocatingly mounted in said casing and provided with a portion that projects laterally through the casing, a keeper that co-operates with said latch to hold the door closed, a spring in the casing that exerts pressure on said latch, and a removable member on said casing arranged in such a manner that the removal of same permits said spring to be withdrawn from the casing.
2. A door lock, comprising a casing, a latch reciprocatingly mounted in said casing and provided with a portion that projects laterally through the casing, a keeper that co-operates with said latch to hold the door closed, an expansion spring that exerts pressure on said latch, said casing having an integral portion that houses said spring, and an abutment member for said spring removably mounted in the integral portion of the casing in such a way that after it has been removed from the casing said spring can be withdrawn from the casing.
3. A door lock, comprising a casing, a

- 4
- latch reciprocatingly mounted in said casing and provided with a portion that projects outwardly through the casing, a keeper that co-operates with said latch to hold the door closed, a spring in the casing that exerts pressure on the latch, a guide in the casing surrounded by said latch and spring, and a removable member on the casing that holds said spring under compression and which is adapted to be removed so as to enable said spring to be withdrawn from the casing.
5. A door lock, comprising a casing, a reciprocating latch in said casing provided with a portion that projects outwardly through the casing, a keeper that co-operates with said latch to hold the door closed, a spring in the casing that exerts pressure on the latch, said casing having an integral portion that serves as a housing for said latch and spring, a guide in the casing surrounded by said latch and spring, and an abutment member for said spring arranged at one end of the spring housing on the casing and detachably connected to the same in such a way as to permit said spring and guide to be removed from the casing.
6. A door lock, comprising a casing, a latch in said casing provided with a portion that projects outwardly through the casing, a keeper that co-operates with said latch to hold the door closed, a coiled expansion spring in the casing for actuating said latch, a guide for said spring, an annular abutment member for said spring surrounding said guide and arranged in an opening in the casing, said abutment member being separate and distinct from said guide, and a removable means for maintaining said abutment member and guide in operative position in the casing.
7. A door lock, comprising a casing, a reciprocating latch in said casing provided with a portion that projects laterally through the side wall of the casing, a keeper that is adapted to co-operate with said latch to hold the door closed, means for disengaging the latch from the keeper, a means on the casing for holding the latch in an inoperative position, a tripping device for disengaging the latch from said means when the door is moved into its closed position, and a spring that exerts pressure on said latch in a direction tending to move it into engagement with said holding means after the latch has been disengaged from the keeper and in a direction tending to move the latch into engagement with the keeper after the latch has been disengaged from said holding means.
8. A door lock, comprising a casing, a reciprocating latch in said casing provided with a portion that projects laterally through the side wall of the casing, a keeper that is adapted to co-operate with said latch to hold the door closed, means for disengaging the latch from the keeper, a means on the casing for holding the latch in an inoperative position, a tripping device for disengaging the latch from said holding means after the latch has been disengaged from the keeper and in a direction tending to move the latch into engagement with the keeper after the latch has been disengaged from said holding means.
9. A door lock, comprising a casing, a reciprocating latch in said casing provided with a portion that projects laterally through the side wall of the casing, a keeper that co-operates with said latch to hold the door closed, a handle on the casing for disengaging the latch from said keeper, a means on the casing for holding the latch in an inoperative position after it has been disengaged from the keeper, a tripping device for disengaging the latch from said holding means when the door is moving into its closed position, and a coiled expansion spring combined with the latch in such a way that the torsional effect of said spring is used to move the latch into engagement with said holding means after the latch has been disengaged from said keeper and the expansive force of said spring is used to move the latch into engagement with the keeper after the tripping device has disengaged the latch from said holding means.
10. A door lock, comprising a casing, a reciprocating latch in said casing provided with a portion that projects laterally through the side wall of the casing, a keeper that co-operates with said latch to hold the door closed, a handle on the casing for disengaging the latch from said keeper, a means on the casing for holding the latch in an inoperative position after it has been disengaged from the keeper, a tripping device for disengaging the latch from said holding means when the door is moving into its closed position, and a coiled expansion spring combined with the latch in such a way that the torsional effect of said spring is used to move the latch into engagement with said holding means after the latch has been disengaged from said keeper and the expansive force of said spring is used to move the latch into engagement with the keeper after the tripping device has disengaged the latch from said holding means.

- in an inoperative position after it has been disengaged from the keeper, a tripping device for disengaging the latch from said holding means when the door is moving into its closed position, a coiled expansion spring combined with the latch in such a way that the torsional effect of said spring is used to move the latch into engagement with said holding means after the latch has been disengaged from said keeper and the expansive force of said spring is used to move the latch into engagement with the keeper after the tripping device has disengaged the latch from said holding means, means for enabling the tension of said spring to be varied, and means for enabling said spring to be withdrawn from the casing without disconnecting the casing from the part which carries same.

11. A door lock, comprising a casing, a guide in said casing, a latch reciprocatingly mounted on said guide and provided with a portion that projects laterally through the side wall of the casing, a keeper that co-operates with said latch to hold the door closed, a handle on the casing for disengaging the latch from said keeper, a means on the casing for holding the latch in an inoperative position after it has been disengaged from the keeper, a device on the keeper for tripping said latch, a coiled expansion spring on said guide that exerts pressure on the latch in a direction tending to cause it to snap into engagement with said holding means after the latch has been disengaged from the keeper and in a direction tending to move the latch into engagement with the keeper after the latch has been tripped, and a removable member detachably connected to the casing that serves as an abutment for said spring and which also operates to hold said guide in operative position.

12. A door latch, comprising a casing, a vertically-disposed guide rod in said casing, a latch reciprocatingly mounted on said guide rod and provided with a portion that projects laterally through the side wall of the casing, a keeper that co-operates with said latch to hold the door closed, a pivotally mounted handle on the casing for disengaging the latch from said keeper, a coiled expansion spring on said guide that exerts pressure on said latch, and a removable abutment member for said spring arranged at the upper end of said guide and detachably connected to the casing.

13. A door latch, comprising a casing, a vertically-disposed guide rod in said casing, a latch reciprocatingly mounted on said guide rod and provided with a portion that projects laterally through the side wall of the casing, a keeper that co-operates with said latch to hold the door closed, a pivotally mounted handle on the casing for disengaging the latch from said keeper, a coiled expansion spring on said guide that exerts pressure on said latch, a removable abutment member for said spring arranged at the upper end of said guide and detachably connected to the casing.

14. A door latch, comprising a casing, a vertically-disposed guide rod in said casing, a latch reciprocatingly mounted on said guide rod and provided with a portion that projects laterally through the side wall of the casing, a keeper that co-operates with said latch to hold the door closed, a pivotally mounted handle on the casing for disengaging the latch from said keeper, a coiled expansion spring on said guide that exerts pressure on said latch, a removable abutment member for said spring arranged at the upper end of said guide and detachably connected to the casing, a tensioning device on said guide arranged between said abutment member and said spring and adapted to be turned to vary the tension of said spring.

15. A door lock, comprising a casing provided in both of its side walls with vertically-disposed slots, a reversible latch in the casing that is adapted to be arranged in a position wherein a portion of same projects laterally through the slot in one of the side walls of the casing, a handle on the casing for disengaging the latch from the keeper constructed so that it will co-operate with the latch in either position of same, a spring in the casing that exerts pressure on the latch, a shoulder on the casing arranged so that the latch will snap into engagement with same after it has been disengaged from the keeper, and a tripping device on the keeper that disengages the latch from said shoulder when the door is moving into its closed position.

16. A door lock, comprising a casing provided in both of its side walls with vertically-disposed slots, a reversible latch in the casing that is adapted to be arranged in a position wherein a portion of same projects laterally through the slot in one of the side walls of the casing, a handle on the casing for disengaging the latch from the keeper constructed so that it will co-operate with the latch in either position of same, a spring in the casing that exerts pressure on the latch, a shoulder on the casing arranged so that the latch will snap into engagement with same after it has been disengaged from the keeper.

with same after it has been disengaged from the keeper, a tripping device on the keeper that disengages the latch from said shoulder when the door is moving into its closed position, and a reversible plate provided with a shank on which the keeper is adjustably mounted.

17. A door lock, comprising a casing adapted to be connected to a door, a vertically-disposed guide rod in said casing, a reversible latch reciprocatingly mounted on said guide rod and provided with a portion that projects laterally through the side wall of the casing, a keeper that co-operates with said latch to hold the door closed, a support for said keeper on which the keeper is adjustably mounted in such a way that it can be arranged in various positions, a pivotally mounted handle on the front side of said casing for disengaging the latch from the keeper, a shoulder on the casing for maintaining the latch in an inoperative position, a coiled expansion spring on said guide that exerts pressure on said latch in a direction tending to force the latch towards the keeper and towards said shoulder, a handle operating member in the door arranged so that the handle can be actuated from the inside of the door.

18. A door lock, comprising a casing 30 adapted to be connected to a door, a vertically-disposed guide rod in said casing, a reversible latch reciprocatingly mounted on said guide rod and provided with a portion that projects laterally through the side wall 35 of the casing, a keeper that co-operates with said latch to hold the door closed, a support for said keeper on which the keeper is adjustably mounted in such a way that it can be arranged in various positions, a pivotally mounted handle on the front side of said casing for disengaging the latch from the keeper, a shoulder on the casing for maintaining the latch in an inoperative position, a coiled expansion spring on said guide that 40 exerts pressure on said latch in a direction tending to force the latch towards the keeper and towards said shoulder, a handle operating member in the door arranged so that the handle can be actuated from the inside 45 of the door, a removable member at the upper end of the casing that surrounds the upper end portion of said guide, a pin that passes transversely through said guide, removable member and casing, and an adjustable device on said guide for varying the 50 tension of said spring.

ADOLPH RUBIN.
